C. W. HUCKINS

FISHING BOAT

Filed July 3, 1923

INVENTOR

Charles W. Huckins
Harry Bowen
ATTORNEY

UNITED STATES PATENT OFFICE.

CHARLES W. HUCKINS, OF SEATTLE, WASHINGTON.

FISHING BOAT.

Application filed July 3, 1923. Serial No. 649,195.

To all whom it may concern:

Be it known that I, CHARLES W. HUCKINS, a citizen of the United States, residing at Seattle, in the county of King and State 5 of Washington, have invented a new and useful Fishing Boat; and I do hereby declare that the following is a full, clear, and exact specification, such as will enable others skilled in the art to which it appertains 10 to make and use the same.

The invention is a small boat similar to a miniature scow, which is constructed of a light material so that it may readily be carried by one man or placed on the running board of a motor vehicle.

The object of the invention is to provide a small one man fishing boat that is absolutely safe.

Another object of the invention is to provide a small fishing boat that may easily be carried on the running board of a motor vehicle.

Another object of the invention is to provide a small boat that may readily be strapped to the running board of a motor vehicle, which may also be used as a packing box.

And a still further object of the invention is to provide a small boat that may readily be strapped on the running board of a motor vehicle, which is of a simple and economical construction and made of a light weight material.

With these things in view the invention embodies a small rectangular shaped boat, having the bottom curved upward at the ends; a seat in it, cleats for holding the oar locks, and a socket for holding a fishing rod.

Other features and advantages of the invention will appear from the following description taken in connection with the drawings, wherein:

Figure 1 is a plan view.

Figure 2 is a longitudinal section.

Figure 3 is an end view.

Figure 4 is a cross section.

Figure 5 is a plan view showing an alternate design.

In the drawing I have shown my boat as it would appear, wherein numerals 1 and 2 indicate the side members, which may be made of a piece of flat board with the ends curved as shown in Figure 2, to form the bottom of the boat. A row of thin boards 3 may be fastened to the edges of the members 1 and 2, and a cleat 4, which may be

shaped as shown in Figure 2 with its ends curved upward, may be attached to the boards 3 between the side boards 1 and 2. A narrow board 5 may be attached to the top of the boat at the forward end, and a wider board 6 may be attached to the top at the rear.

A seat 7 may be placed across the boat and supported at the sides by cleats 8 and 9, and at the center by a stanchion 10 as shown in Figure 4. Cleats 11 may be placed on the sides, to which sockets 12 may be attached for holding the oar locks, and a cylindrical shaped socket 13 may be placed on the side, 70 in which a fishing rod may be held.

In Figure 5 I have shown an alternate design in which the corners at the front may be beveled as shown, so that it will be possible to place a longer boat on the running board, as the lower beveled corner may be placed against the front fender. In this design I have also shown two seats 14 and 15 in place of the seat 7 as shown in Figure 1, and also three cleats 16, 17 and 18 in place 80 of the single cleat 4 shown in Figure 1. A boat of this type may be made longer so that it will hold two persons instead of one, and by using more cleats in the bottom it will be possible to use very thin boards for 85 covering the bottom.

The structure of the boat may be made of thin light weight boards, the exterior of which may first be given a coat of a priming substance to fill the wood, when a coat 90 of shellac or the like, then covered with canvas or the like which will be held to the wood by the shellac, this will be covered by a coat of white lead, or the like, and then covered with paint or enamel. The canvas 95 will be placed on the frame as shown in Figure 4, with strips 19 on the sides, which are bent under at the bottom, and a large sheet 20, which will cover the entire bottom and lap over the edges of the strips 100 19. Cleats 21 may be attached to the boat over the canvas to protect the corners, edges and bottom and strips 22, which may be made of leather or other suitable material, may be placed over the corners at the ends. 105

It will be understood that changes may be made in the construction without departing from the spirit of the invention. One of which changes may be in the design, shape or size of the boat, as it is understood that this may be made of any suitable shape or size that will conform with the general de-

sign shown. Another change may be in the use of smaller boards in place of the boards 3, which may be arranged with spaces between them. And still another change may 5 be in the location of the sockets for holding the oar locks, or fishing rod, as it is understood that as many of these as may be desired may be used, and they may be placed in any desired position.

10 The construction will be understood from the foregoing description. To use the device it will be seen that it may readily be carried on the running board of a motor vehicle, by placing one edge upon the running board, with the bottom outward, and the other edge upward, so that from the outside it will have the appearance of a rectangular shaped box with curved ends. A strap may be placed around the boat and the 15 ends attached to the body of the vehicle in any suitable manner. The oars may be placed on the inside, as very short oars, which may be placed under the seat will be sufficient. It will also be seen that practically the entire camping outfit may be placed inside of the boat and by covering it with a tarpaulin the interior may be kept absolutely dry.

25

Having thus fully described the invention, 30 what I claim as new and desire to secure by Letters Patent, is:

1. A small fishing boat for motor vehicles, having flat sides with the edges curved upward at the ends, boards forming the bottom attached to the lower edges of the sides,

35

cleats attached to the boards on the inside, between the sides, other cleats attached to the sides and boards at the ends and on the top, a transverse board forming a seat attached to the sides by cleats and supported at the center by a stanchion, and other cleats attached to the upper inner edges of the sides with sockets on them for holding the oar locks; and one of said sides having a cylindrical socket for holding a fishing rod; and the exterior of said boat being first coated with a wood filler, then covered with shellac, or the like, then canvassed with the edges lapped, then covered with white lead or the like, and then painted or enameled. 40

2. A small fishing boat for motor vehicles, having flat sides with the edges curved upward at the ends, boards forming the bottom attached to the lower edges of the sides, cleats attached to the boards on the inside, between the sides, other cleats attached to the sides and boards at the ends and on the top, a transverse board forming a seat attached to the sides by cleats and supported at the center by a stanchion, other cleats attached to the upper inner edges of the sides, with sockets on them for holding the oar locks; other cleats for protecting the corners, edges and bottom; the exterior of said frame being first coated with a wood 45 filler, then covered with shellac, or the like, then canvassed with the edges lapped, then covered with white lead or the like, and then painted or enameled. 50
